(57) **CLAIM**

The ornamental design for a set of inner cup and outer cup, as shown and described.

DESCRIPTION

FIG. 1 is a perspective view of a set of inner cup and outer cup showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view taken along the line 8-8 in FIG. 6; and,

FIG. 9 is an enlarged view of the portion 9 of FIG. 8.

The broken lines illustrate portions of the set of inner cup and outer cup that form no part of the claimed design.

1 Claim, 8 Drawing Sheets
